UNITED STATES PATENT OFFICE.

HERBERT PEARCE, THOMAS ROBERT GILLETT PARKER, AND FRED WESLEY WRIGHT,
OF BROADHEATH, ENGLAND, ASSIGNORS TO LINOTYPE AND MACHINERY LIMITED,
OF LONDON, ENGLAND.

DELIVERY-BOARD FOR PRINTING AND OTHER MACHINES.

1,088,360.

Specification of Letters Patent.

Patented Feb. 24, 1914.

Application filed July 22, 1912. Serial No. 710,887.

To all whom it may concern:

Be it known that we, HERBERT PEARCE, THOMAS ROBERT GILLETT PARKER, and FRED WESLEY WRIGHT, subjects of the King of the United Kingdom of Great Britain and Ireland, residing at Linotype and Machinery Works, Broadheath, in the county of Chester, England, have invented new and useful Improved Delivery-Boards for Printing and other Machines, of which the following is a specification.

The subject of the present invention is an improved delivery board to receive the sheets that are delivered from a printing or other machine which deals with its material in sheet form and delivers the sheets successively.

The object of it is to provide improved means for effecting a partial or entire withdrawal of the board from the machine in such a way as to give a corresponding access to the parts of the machine that are adjacent to the inner edge of the board and to provide that such partial withdrawal of the board may be effected without disturbing already delivered sheets thereon or removing them therefrom. A preferred form of structure by which the said object is attained, is illustrated in the accompanying drawings in which—

Figure 1 is a side elevation and Fig. 2, a partial vertical section on the line 2—2 of Fig. 1.

There projects from each side of the delivery end of the machine, a suitable support comprising in this instance an upwardly-extending arm *a*, and on this is preferably mounted a horizontal rail 1, the two rails being parallel with each other. Each side of the delivery board 2 carries a plurality of rollers 3, 4, 5, suitably spaced apart according to the predetermined distance which said board must be shifted to permit access to the parts of the machine that are adjacent to the inner edge of the board 1, the rollers on one side of the board having their axes respectively aligned with those on the other side. Each set of rollers engages with the respective rail 1 in such a way that the board 2 can travel on the pair of rails 1, 1, to and from the said adjacent parts, the connection of the board 2 to the inner pair of rollers 3 being of a pivotal nature so that the board

can, as a whole, be swung upon the axis 6 of that pair. These adjacent parts are not included in the figures—they are to be taken as being on the left hand of Fig. 1 and behind Fig. 2. There is a stop 7 on the end of each rail next to the machine the end of which is indicated at 8, and with which stop, engage the frames 9 that carry the inner set of rollers 3, to indicate when the board 2 has been pushed home into sheet-receiving position. One of the rails 1 has means for stopping the board in any of its plurality of positions of rest, such a series of holes or sockets 10, 11, 12, spaced apart on the same principle as the rollers, and a pin 13 loosely attached to it so as to be put into the respective hole 10, 11 or 12, outside the respective frame 9 above mentioned, and stop any, or a further, withdrawal of the board 2. Thus, supposing three degrees of access are desired, there are three pairs of traveling rollers 3, 4, 5, and three holes 10, 11, 12. When the pin 13 is in the hole 10, *i. e.*, in the one next to the machine, it locks the board 2 in its working position. When it is in the intermediate hole 11, a corresponding access is afforded, the outer pair of rollers 5 being then clear of the rails 1 and the board 2 kept parallel with them by the two inner pairs of rollers 3 and 4. When it is in the outer hole 12, a corresponding but greater access is afforded and the board 2 can then swing down clear of the outer ends of the rails 1. When it is in none of the holes, the board 2 as a whole can be withdrawn from the machine, thus affording a third and still greater access to the parts of the juxtaposed machine. The pair of frames carry additional rollers 14 to engage with the bottom edges of the rails 1.

15 is an upstanding sheet stop on the front of the board 2—it does not form any part of the present invention.

Having described our invention, we declare that what we claim and desire to secure by Letters Patent is:—

1. A structure of the kind specified including in combination, a pair of board-sustaining rails disposed in juxtaposition to a printing machine, a traveling sheet-delivery board on said rails, a board-limiting stop disposed to arrest the board at a point in relatively close proximity to said machine, and a shiftable stop element distinct from

said board-limiting stop for arresting the machine at points different distances therefrom.

2. A structure of the type specified including a support, a traveling sheet-delivery board on said support, cooperating means on the support and board for arresting the board at any of a plurality of predetermined points on its support whereby the board may 5 be positioned and retained at a point remote 10 from a machine to which it is normally juxtaposed and, also at intermediate points, and pivotal-means carried by the support and board for permitting said board 15 to be swung to a position at an angle to its normal plane of travel.

3. A structure of the kind specified, including in combination, a support adapted to be disposed in juxtaposition to a printing 20 machine, a sheet-delivery board on said support, a pair of board-sustaining rails carried by the support, a series of rollers carried by the board and adapted to traverse the rails, a board limiting-stop disposed to 25 arrest said board at a point in juxtaposition to said machine, and means distinct from said board limiting-stop and adapted to arrest the machine at points different distances from said limiting-stop.

30 4. A structure of the kind specified including in combination, a support adapted to be disposed in juxtaposition to a printing machine, a sheet-delivery board on said support, a pair of board-sustaining rails carried by the support, a series of rollers carried by the board and adapted to traverse the rails, a board limiting-stop disposed to 35 arrest said board at a point in juxtaposition to said machine, and means distinct from 40 said board limiting-stop and including a movable element adapted to arrest the machine at points different distances from said limiting-stop and when arranged in proximity to said limiting-stop to lock the 45 board in its sheet-receiving position.

5. A structure of the kind specified including in combination, a support adapted to

be disposed in juxtaposition to a printing machine, a sheet-delivery board on said support, a pair of board-sustaining rails carried by the support, a series of rollers carried by the board and adapted to traverse the rails, a board limiting-stop disposed to arrest said board at a point in juxtaposition to said machine, at least one of which rails 50 is provided with means adapted to arrest the machine at points different distances from said limiting-stop and operating when disposed in proximity to said limiting-stop to lock the board in its sheet-receiving position, and roller-carrying frames connected to and traveling with said board and adapted 55 to engage one or another of said stops.

6. A structure of the kind specified including in combination, a support adapted to be disposed in juxtaposition to a printing machine, a sheet-delivery board on said support, a pair of board-sustaining rails carried by the support, a series of rollers carried by the board and adapted to traverse the rails, 60 a board limiting-stop disposed to arrest said board at a point in juxtaposition to said machine, at least one of which rails is provided with means adapted to arrest the machine at points different distances from said 65 limiting-stop and operating when disposed in proximity to said limiting-stop to lock the board in its sheet-receiving position, roller-carrying frames connected to and traveling with said board and adapted to 70 engage one or another of said stops, and pivot-means interposed between the board and frames whereby said board may have a swinging movement in addition to its traveling movement.

85 In witness whereof we have hereunto set our hands in the presence of two witnesses.

HERBERT PEARCE.
THOMAS ROBERT GILLETT PARKER.
FRED WESLEY WRIGHT.
